(57) **CLAIM**

The ornamental design for a neuro headset for electroencephalogram recording with quality control of electrodes installation, as shown and described.

DESCRIPTION

FIG. 1 is a front view of a neuro headset for electroencephalogram recording with quality control of electrodes installation;

FIG. 2 is a rear view thereof;

FIG. 3 is a left side view thereof;

FIG. 4 is a right side view thereof;

FIG. 5 is a top view thereof;

FIG. 6 is a rear right perspective view thereof;

FIG. 7 is a rear left perspective view;

FIG. 8 is an overall view thereof;

FIG. 9 is a right side view thereof; and,

FIG. 10 is a left side view thereof.

The broken lines in the drawings depict environmental subject matter and form no part of the claimed design.

1 Claim, 10 Drawing Sheets
